CLAIM

The ornamental design for a drawer as shown and described.

DESCRIPTION

FIG. 1 is a top, front, right perspective view of the drawer; FIG. 2 is a front elevation view of the drawer of FIG. 1; FIG. 3 is a back elevation view of the drawer of FIG. 1; FIG. 4 is a left elevation view of the drawer of FIG. 1; FIG. 5 is a right elevation view of the drawer of FIG. 1; FIG. 6 is a top plan view of the drawer of FIG. 1; FIG. 7 is a bottom elevation view of the drawer of FIG. 1; and, FIG. 8 is a front cross-sectional view of the drawer of FIG. 1 along the line shown in FIG. 6.

The broken lines in FIGS. 1-8 are included for the purpose of illustrating portions of the drawer that form no part of the claimed design. A separation and a bracket in FIGS. 1-8 are included to indicate that the precise length, width, and/or height of the drawer are not claimed.

1 Claim, 8 Drawing Sheets
